The ornamental design for an electrical wiring device, as shown and described.

DESCRIPTION

FIG. 1 is an isometric view of a first embodiment of an electrical wiring device showing my new design;

FIG. 2 is a front view thereof;

FIG. 3 is a side view thereof;

FIG. 4 is an end view thereof;

FIG. 5 is a front view thereof shown in an environment of use;

FIG. 6 is an isometric view of a second embodiment of an electrical wiring device showing my new design;

FIG. 7 is a front view thereof;

FIG. 8 is a side view thereof; and,

FIG. 9 is an end view thereof.

The broken lines in the figures illustrate unclaimed environment only and form no part of the claimed design.
